DESIGN FOR A BENCH CENTER

Clifford Brooks Stevens, Milwaukee, Wis., assignor, by mesne assignments, to The Delta Manufacturing Company, a corporation of Delaware

Application August 3, 1944, Serial No. 114,714

Term of patent 14 years

(Cl. D54—6)

To all whom it may concern:

Be it known that I, Clifford Brooks Stevens, a citizen of the United States, residing at Milwaukee, in the county of Milwaukee and State of Wisconsin, have invented a new, original, and ornamental Design for Bench Center, of which the following is a specification, reference being had to the accompanying drawings forming a part thereof.

Figure 1 is a top plan view of a bench center embodying my new design;

Figure 2 is a front elevational view of the bench center of Figure 1;

Figure 3 is a rear elevational view of the bench center of Figures 1 and 2, and

Figure 4 is an end elevational view of the bench center of Figures 1 to 3 as seen from the right hand end of Figure 1, the opposite end being identical except for the quick release lever and mechanism provided for the tailstock center shown to the right of Figure 1.

I claim:

The ornamental design for a bench center, as shown and described.

CLIFFORD BROOKS STEVENS.
